UNITED STATES PATENT OFFICE.

CHARLES MANFIELD JOHNSON, OF MILWAUKEE, WISCONSIN, ASSIGNOR, BY DIRECT AND MESNE ASSIGNMENTS, OF ONE-HALF TO CHARLES H. COAKLEY, WILLIAM F. COAKLEY, AND STEPHEN S. CRAMER, OF MILWAUKEE, WISCONSIN.

BOX-FASTENER.

SPECIFICATION forming part of Letters Patent No. 694,480, dated March 4, 1902.

Application filed November 11, 1901. Serial No. 81,834. (No model.)

To all whom it may concern:

Be it known that I, CHARLES MANFIELD JOHNSON, a citizen of the United States, and a resident of Milwaukee, in the county of Milwaukee and State of Wisconsin, have invented certain new and useful Improvements in Box-Fasteners; and I do hereby declare that the following is a full, clear, and exact description thereof.

10 My invention has for its object to provide simple economical box-fasteners organized with especial reference to the utilization of metallic seals in connection therewith; and it consists in certain peculiarities of construction and combination of parts hereinafter particularly set forth, with reference to the accompanying drawings, and subsequently claimed.

Figure 1 of the drawings represents a partly-20 sectional front elevation of one of my improved fasteners and illustrates the same in connection with portions of a box wall and lid; Fig. 2, a sectional view on the plane indicated by line 2 2 in the first figure; and 25 Fig. 3, a plan view, partly in horizontal section, as indicated by lines 3 3 in said first figure.

Referring by letter to the drawings, A indicates a sheet-metal plate having an upper 30 right-angle flange b, provided with a longitudinal slot c, and an outer lip d is shown depending from the flange; but while I have shown the lip it may be omitted if not found necessary or desirable. Central of the plate 35 the metal thereof is cut out to form preferably circular apertures e f, one below the other, and an apertured outer lateral ear g is shown struck up from said plate, although it may be made separate from the same and attached thereto.

Riveted or otherwise secured at its lower end to plate A is a strip B of spring metal, provided with outer lugs h i, that extend through the apertures e f of said plate.

45 The construction and arrangement of parts thus far described constitutes the bolt portion of a box-fastener in accordance with my invention, the catch portion of said fastener being a strip C of sheet metal bent to form a

right angle, its vertical or tongue portion being provided with a central aperture j and an apertured outer lateral corner ear k, this ear being preferably an integral portion of said strip.

In practice plate A of the bolt portion of the fastener is fitted on a wall D of a box and made fast thereto by nails or screws driven into the wall through apertures provided in said plate, the upper longitudinally-slotted flange b of this plate being flush on the upper edge of the box-wall, and the flange-lip d, if employed, faces the outside of said wall and a recess provided there. The box-wall recess is closed at the back by plate A, and the slot c in plate-flange b registers with the recess. The catch portion C of the fastener is made fast to the under side of a swing-lid E of the box in position to have its tongue extend through the flange-slot c of plate A when the lid is swung down. The catch-tongue 70 in its descent strikes the rounded or beveled edge of lug h of spring-plate B pertaining to the bolt portion of the fastener, and said plate is automatically retracted to effect a clearance of said tongue by said lug. The lid being full down, the aperture of the fastener-tongue is automatically engaged by the lug h of spring-plate B, this plate being then in normal position. The lid having been automatically fastened in closed position, the 80 strap or wire of an ordinary metallic seal F may be engaged with the plate and tongue-ears g k, as is herein shown. The seal being broken or absent, the lug i of spring-plate B is pushed upon to retract said plate and disengage lug h of same from the tongue-aperture of the latch portion of the fastener, so that the box-lid may be swung back on its hinges.

Having thus described my invention, what I claim as new, and desire to secure by Letters Patent, is—

1. A box-fastener comprising a main plate attachable to a box-wall back of a recess therein, a spring-plate fast at one end to the main plate and provided with lugs extending through apertures in said main plate one below the other, and a catch consisting of a

right-angle strip attachable to the under side of a box-lid, its vertical or tongue portion being apertured and engageable with the upper lug of the spring-plate when said lid is swung down.

2. A box-fastener comprising a main plate attachable to a box-wall back of a recess therein and having a longitudinally-slotted right-angle flange that faces the upper edge of the box-wall over said recess, a spring-plate fast at one end to the main plate and provided with lugs extending through main plate apertures one below the other, and a catch consisting of a right-angle strip attachable to the under side of a box-lid, its vertical or tongue portion being apertured and engageable with the upper lug of the spring-plate when said lid is swung down.

3. A box-fastener comprising a main plate attachable to a box-wall back of a recess therein, and provided with an outer apertured lat-

eral ear, a spring-plate fast at one end to the main plate and provided with lugs extending through apertures in said main plate one below the other, a catch consisting of a right-angle strip attachable to the under side of a box-lid, its vertical or tongue portion being apertured and engageable with the upper lug of the spring-plate when said lid is swung down, and an apertured ear extending outward from the catch-tongue, the strap or wire of an ordinary metallic seal being engageable with the main plate and catch-tongue ears.

In testimony that I claim the foregoing I have hereunto set my hand, at Milwaukee, in the county of Milwaukee and State of Wisconsin, in the presence of two witnesses.

CHARLES MANFIELD JOHNSON.
